UNITED STATES PATENT OFFICE

ROBERT E. CAINE, OF BATTLE CREEK, MICHIGAN.

SALT-BOX.

SPECIFICATION forming part of Letters Patent No. 286,384, dated October 9, 1883.

Application filed February 23, 1883. (No model.)

To all whom it may concern:

Be it known that I, ROBERT E. CAINE, of Battle Creek, in the county of Calhoun and State of Michigan, have invented a new and 5 Improved Salt-Box, of which the following is a full, clear, and exact description.

The object of my invention is to provide a new and improved receptacle for containing salt and distributing the same evenly over the 10 articles of food to be salted.

The invention consists of a salt box or receptacle containing a central shaft, operated from the exterior of the box by means of a crank-handle. The shaft is centrally journaled within the box, and is provided with one 15 or more stirring devices—such as a screw-propeller or other form of arms—whereby when the shaft is turned the salt will be loosened or broken up, if caked, thereby promoting the 20 escape of the salt from the perforated cap of the receptacle, as hereinafter fully described, and pointed out in the claims.

Reference is to be had to the accompanying drawings, forming part of this specification, in 25 which similar letters of reference indicate corresponding parts in all the figures.

Figure 1 is a longitudinal sectional elevation of my improved salt-box. Fig. 2 is a sectional plan view of the same on the line *x* *x*, 30 Fig. 1. Fig. 3 is a plan view of the upper agitating wings or blades. Fig. 4 is a perspective view of the bottom agitating-arms.

A receptacle, A, of metal, glass, porcelain, or other suitable material, is provided with a 35 perforated removable cap, B. A shaft, C, is journaled in the bottom D of the vessel and in the cap B, which shaft extends centrally and longitudinally through the vessel, which shaft is provided, below the bottom, with a crank- 40 handle, E, which is surrounded by the base F. On the shaft C a screw-blade, G, of the diameter of the vessel, is rigidly mounted. On the upper end of the shaft C two opposite blades, H, are mounted, the upper edges of which are 45 in close proximity to the under surface of the perforated cap B. The upper edges of the

blades H are bent over in opposite directions. On the lower end of the shaft C a series of rods or arms, J, are mounted, which project in opposite directions. The receptacle can 50 be provided with a handle, K, if desired.

The device is used as follows: As is well known, salt absorbs moisture and clogs, and can then only be sifted through the perforated cap with great difficulty. If the receptacle is inverted and the crank-handle E is turned, the blades H and the rods J loosen the salt and break the lumps, and the screw-blade G forces the salt toward the perforated cap, and the blades H press the salt through 60 the perforations in the cap. The salt will then be distributed evenly over the article to be salted, and the quantity of salt to be sifted on the article can be easily gaged. The blades H remove the salt that collects on 65 the bottom of the cap. The device can also be used for all kinds of spices, but is specially adapted for salt.

Having thus described my invention, I claim as new and desire to secure by Letters Patent— 70

1. In a salt-box, the combination, with a receptacle, of a shaft journaled in the same, a screw-blade mounted on the shaft, and a handle for turning it, on the end of the shaft below the bottom of the receptacle, substantially as 75 herein shown and described, and for the purpose set forth.

2. In a salt-box, the combination, with the receptacle A, of the shaft C, journaled therein, the handle E, the screw-blade G, and the blades 80 H, substantially as herein shown and described, and for the purpose set forth.

3. In a salt-box, the combination, with the receptacle A, of the shaft C, journaled in the same, the handle E, the screw-blade G, blades 85 H, and the rods J, substantially as herein shown and described, and for the purpose set forth.

ROBERT E. CAINE.
